(57) **CLAIM**

The ornamental design for a diaper shaped container, as shown and described.

DESCRIPTION

FIG. 1 is a front-right elevational perspective of the present design with a safety pin (in phantom) appearing to hold the diaper closed;

FIG. 2 is a front view of the diaper shaped container of the present design;

FIG. 3 is a right side view of the diaper shaped container of the present design;

FIG. 4 is a top plan view of the diaper shaped container of the present design; and,

FIG. 5 is a bottom plan view of the diaper shaped container of the present design.

The broken line showing of the safety pin is for illustrative purposes only, and forms no part of the claimed design.
